UNITED STATES PATENT OFFICE.

ARMAND JACQUELIN, OF PARIS, FRANCE.

GRID OR RIDDLE FOR SIFTING MINERALS, COAL, AND OTHER MATERIALS.

Application filed December 28, 1921. Serial No. 525,437.

To all whom it may concern:

Be it known that I, ARMAND JACQUELIN, citizen of the Republic of France, residing at 11, Avenue Pasteur, Paris, France, have 5 invented certain new and useful Improvements in or Relating to Grids or Riddles for Sifting Minerals, Coal, and Other Materials, of which the following is a specification, reference being had therein to the 10 accompanying drawing.

My invention relates to grids or riddles for sifting minerals, coal and other materials.

According to this invention the grid or 15 riddle is constituted by a continuous metallic wire, wound around a frame, then stretched, the upper strands of this wire being arranged in a certain number of planes parallel with each other, and the lower 20 strands being connected in bundles of two or more.

A grid or riddle according to this invention is represented by way of example in the accompanying drawing in which:

25 Figure 1 is a partial top plan view of the grid or riddle, the lower strands of the wire not being shown.

Figure 2 is a section of the frame with a plan view of the lower strands of the riddle.

30 Figures 3 and 4 are a longitudinal elevation and a side elevation respectively of the grid.

Figure 5 is a partial longitudinal section of a modification of the frame.

35 The sifting grid or riddle is formed by a continuous steel wire 1 of high elastic resistance, subjected to a high tension, after being rolled around an extensible metallic frame constituted by two steel bars 2, of round 40 cross-section or having rounded edges, connected together by a sufficient number of stretcher bolts 3. The two ends of the wire are strongly secured by being firmly clamped for example between one of the bars and the 45 single or double nut of a screw-threaded stud 4.

The position of the strands of the wire on the frame is exactly determined by two series of notches 5, 6 uniformly and suitably 50 spaced apart, and made in the upper and lower faces respectively of the bars 2 and in which notches the wire lies. The whole of the upper strands 7 of the wire constituting the grid proper.

55 The lower strands 8 are connected together in groups of two or more, in the

notches 6 and each of these groups of strands is clamped into a bundle by certain runners 9 of annealed steel wire. This special arrangement of the lower strands has for its 60 object to afford a free passage to the products which have passed through the riddle without obstruction.

The upper strands may be arranged in one and the same plane as shown in Figures 1 65 to 4.

It is obvious that series of notches 5 may be provided, the various notches of one and the same series being of different depths. In this case the upper strands are arranged 70 in planes which are parallel with other, and equal in number to the number of notches in one and the same series. For example the notches 5 may have alternately two different depths (see Figure 5) in which 75 case the upper strands of the steel wire are in two planes parallel with each other.

In order to facilitate the exit of the product to the front end of the riddle the corresponding bar 2 has fixed on it a strip of 80 sheet metal 10 the effect of which is to raise the grains partially held between two adjacent strands of the riddle.

The above described grid or riddle is strong and possesses great sifting capacity 85 by reason of the relative size of the gaps with respect to the solid parts.

It offers no serious risk of obstruction, even when the strands are very close together by reason of the elasticity of the 90 metal of the wire combined with its tension.

For this latter reason there is no longer any reason to fear any permanent change of shape in the wire which would bring about appreciable variations in the gaps 95 separating the strands.

This sifting grid is of particular value for the removal of dust from any kind of raw material, particularly when it is damp. It is of great use even when erected in a stationary form, but it gives the best results when it is combined with an oscillating sieve, particularly when the oscillations are of high frequency.

The direction of the wires may be that of 105 the advance of the products to be sifted or may be at right angles or even obliquely thereto.

The particular arrangement of the grid with wires at alternate levels also increases 110 the separating power of the grid and facilitates the easy elimination of flat grains in

2
a category of products of any kind, previously classified in diameter on perforated metal sheets. This special operation is of use in particular when applied to the double preliminary classification (in diameter and thickness) of minerals and fuels before they are washed, and in the mechanical removal of stone from coals when the greater of the schists is in a more or less flattened form as is very frequently the case.

10 I claim:—

1. A sifting grid comprising a continuous metal wire wound around a frame and then stretched, the upper strands of the wire being arranged in a certain number of parallel planes and the lower strands of the wire being connected in bundles of two or more.
- 15 2. A sifting grid comprising a continuous

metal wire an extensible frame constituted by two bars provided with notches and 20 by connecting cross bars acting as stretchers, each notch of the upper face of the bars corresponding to an upper strand of the wire and each notch of the lower face corresponding to several lower strands of the wire, connected together by binders suitably spaced 25 apart.

3. A sifting grid according to claim 2 in which all the upper strands of the wire are in one and the same plane.

30 In testimony whereof I hereunto affix my signature in the presence of two witnesses.

ARMAND JACQUELIN.
